UNITED STATES PATENT OFFICE

HORACE W. KING, OF BERKELEY, CALIFORNIA, ASSIGNOR TO KING-SEELEY CORPORATION, OF ANN ARBOR, MICHIGAN, A CORPORATION OF MICHIGAN

LIQUID DEPTH INDICATING DEVICE

Application filed December 16, 1926. Serial No. 155,289.

The invention relates to liquid depth indicating devices and refers more particularly to devices for indicating the depth of liquid fuel in motor vehicle supply tanks. One of the objects of the invention is to provide a liquid depth indicating device which is so arranged and constructed that the air within the air chamber is renewed or supplied by the air carried in solution in the liquid fuel. Another object is to provide means for heating the liquid fuel within the air chamber to decrease its capacity to hold air in solution and thus cause excess air to be liberated within the air chamber to maintain the surface of the liquid fuel within the air chamber at a predetermined height. A further object is to provide a simple construction of device for indicating the depth of liquid fuel in the supply tank from which the liquid fuel flows under the influence of gravity. With these as well as other objects in view, the invention resides in the novel features of construction and combinations and arrangements of parts as more fully hereinafter set forth.

In the drawings:—

Figure 1 is a side elevation of a portion of a motor vehicle having applied thereto a liquid fuel depth indicating device embodying my invention;

Figure 2 is a front elevation thereof.

Figure 3 is a section on line 3—3 of Figure 1.

My invention is particularly applicable to a standard make of motor vehicle in which the liquid fuel such as gasoline flows from the liquid fuel supply tank to the carburetor under the influence of gravity. As shown, 1 is the internal combustion engine and 2 the carburetor therefor. 3 is the liquid fuel supply tank located in rear of the engine and in front of the motor vehicle dash and also above the carburetor and 4 is the connection between the tank and the carburetor for conducting the liquid fuel

from the tank to the carburetor under the influence of gravity.

For indicating the depth of liquid fuel in the tank 3 or if desired, the quantity of liquid fuel in this tank, I have provided the depth indicating device 5 which is located in the connection 4 and specifically between the sediment bulb 6 depending from the tank and the pipe 7 leading upwardly from the carburetor. 8 is the air chamber of this device having a relatively large cross sectional area to expose a relatively large surface area of the liquid fuel within the air chamber. This air chamber is located in advance of the tank 3 and in rear of the engine 1 so that it is exposed to heat thrown off from the engine and as a consequence the liquid fuel passing through the air chamber is heated and its capacity to hold air in solution is decreased so that excess air is liberated. This liberated air passes upwardly into the air chamber and maintains the surface of the liquid fuel within the air chamber at a predetermined height.

To facilitate in the liberation of the air carried in solution in the liquid fuel, I provide for moving the surface of the liquid fuel within the air chamber. As shown, 9 is the inlet of the air chamber connected to the sediment bulb and 10 is the outlet of the air chamber connected to the pipe 7, the upper end of the outlet being located above the bottom of the air chamber and preferably adjacent to the normal level of liquid fuel within this air chamber. The inlet and outlet are laterally spaced and located in the bottom of the air chamber so that the liquid fuel in flowing through the air chamber also reverses its direction and facilitates in the liberation of the air carried in solution in the liquid fuel.

For establishing the normal level of liquid fuel within the air chamber, I have provided the vent tube 11 having an open lower end extending within and communi-

cating with the interior of the air chamber 8 below its upper end and also having an open upper end above the tank 3. 12 is a pressure transmitting tube leading from the upper end of the air chamber 8 to one leg of the U-pressure gage 13 which is provided with suitable graduations 14 for indicating either the depth of the liquid fuel in the tank 3 or the quantity of the liquid fuel in this tank.

In operation and assuming the level of liquid fuel in the air chamber 8 to be above the lower open end of the tube 11, upon running of the engine and consequent flow of the liquid fuel from the tank 3 to the carburetor 2 this liquid fuel in passing through the air chamber is heated and has a considerable exposed surface area and furthermore is agitated so that it gives off air which is carried in solution in the liquid fuel. This air collects in the air chamber to displace the liquid fuel therewith down to the open lower end of the tube 11 under which conditions the pressure of the air within the air chamber corresponds to the hydrostatic head of the liquid fuel in the tank 3 down to the level of the open lower end of the tube 11. During the running of the engine air is continually given up by the liquid fuel to maintain the predetermined level of the liquid fuel in the air chamber, any excess air escaping through the tube 11.

What I claim as my invention is:

1. The combination with a liquid fuel tank, a carburetor, and a connection from said carburetor to said tank for permitting said carburetor to receive the liquid fuel under the influence of gravity, of a depth indicating device for the liquid fuel in said tank comprising an air chamber of relatively large cross sectional area in the connection between said tank and carburetor and arranged adjacent the engine, a tube having an open upper end above said tank and an open lower end communicating with the interior of said air chamber below its upper end, a pressure gage, and pressure transmitting means between said pressure gage and the upper end of said air chamber.

2. The combination with a liquid fuel tank, a carburetor and a connection from said carburetor to said tank for permitting said carburetor to receive the liquid fuel under the influence of gravity, of a depth indicating device for the liquid fuel in said tank comprising an air chamber of relatively large cross sectional area in the connection between said tank and carburetor and having an inlet and an outlet in its bottom, said outlet being spaced laterally from the inlet, a tube having an open upper end above said tank and an open lower end within and communicating with the interior of said air chamber below its upper end, a pressure

gage, and pressure transmitting means between said pressure gage and the other end of said air chamber.

3. The combination with an internal combustion engine, a liquid fuel tank, a carburetor for said engine and a connection from said carburetor connected to said tank for permitting said carburetor to receive the liquid fuel under the influence of gravity, of a depth indicating device for the liquid fuel in said tank comprising an air chamber located between said tank and engine, in close proximity to the latter, and having a relatively large cross sectional area providing for the exposure of a relatively large surface of liquid fuel in said air chamber, said air chamber being in the connection between said tank and carburetor, a tube having an open upper end above said tank and an open lower end communicating with the interior of said air chamber below its upper end, a pressure gage, and pressure transmitting means between said pressure gage and the upper end of said air chamber.

4. The combination with a liquid fuel tank, a carburetor, and a connection from said carburetor to said tank for permitting said carburetor to receive the liquid fuel under the influence of gravity, of a depth indicating device for the liquid fuel in said tank comprising an air chamber of relatively large cross sectional area in the connection between said tank and carburetor and provided with an inlet and an outlet in its bottom laterally spaced from each other, said outlet being located adjacent to the normal level of the liquid fuel within said air chamber, a tube having an open upper end above said tank and an open lower end communicating with the interior of said air chamber below its upper end and above said outlet and establishing the normal level of the liquid fuel within said air chamber, a pressure gage, and pressure transmitting means between said pressure gage and the upper end of said air chamber.

5. The combination with an internal combustion engine, a liquid fuel tank and a carburetor for said engine, and a connection establishing communication between said tank and carburetor for supplying liquid fuel to the latter, of a depth indicating device for the liquid fuel in said tank, including an air chamber in said connection and through which the fuel passes and arranged to be heated by said engine, a pressure gage and pressure transmitting means between said pressure gage and the upper end of said air chamber.

6. The combination with an internal combustion engine, a liquid fuel tank and a carburetor for said engine, and a connection establishing communication between said tank and carburetor for supplying liquid

fuel to the latter, of a depth indicating device for the liquid fuel in said tank dependent upon the heat of the engine to liberate air carried in solution in the liquid fuel, said device including an air chamber in said connection and arranged adjacent said engine for receiving the liberated air, a pressure gage and pressure transmitting means between said pressure gage and air chamber.

5   6 In testimony whereof I affix my signature.
HORACE W. KING.
